UNITED STATES PATENT OFFICE.

STEPHEN T. SMITH, JR., OF STAMFORD, CONNECTICUT, ASSIGNOR TO UNDERWOOD TYPEWRITER COMPANY, OF NEW YORK, N. Y., A CORPORATION OF NEW JERSEY.

STENCILING-MACHINE.

No. 848,777.

Specification of Letters Patent.

Patented April 2, 1907.

Application filed June 23, 1906. Serial No. 323,081.

To all whom it may concern:

Be it known that I, STEPHEN T. SMITH, Jr., a citizen of the United States, residing in Stamford, in the county of Fairfield and State 5 of Connecticut, have invented certain new and useful Improvements in Stenciling-Machines, of which the following is a specification.

This invention relates to stenciling or duplicating machines, and particularly to those in which a stencil is wrapped upon a large cylindrical ink-screen, the sheets of paper to be stenciled being run between said ink-screen and a pressure-roller and stripping off from 10 the ink-screen and piling up on the delivery side of the machine, machines of this class being illustrated in Letters Patent No. 832,217. In manufacturing such machines for the market it is desirable to provide a paper-receiving 15 or delivery shelf upon which the stenciled sheets may pile, and this shelf must be of sufficient length to receive the longest sheets that are to pass through the machine, which pile up against the ledge at the end of the 20 shelf. It is found that short sheets passing through the machine do not pile up properly on a shelf which is the suitable length for long sheets, but slide one under another and become disarranged and skewed upon the shelf, 25 thereby tending to rumple the sheets and also rendering it necessary to handle them to an undesirable extent thereafter and besides incurring liability of blurring the fresh ink upon the sheets. In order to overcome this objection, 30 I have devised a shelf which is long enough for the longest sheets and which can be shortened as required to make it the proper length for short or medium length sheets.

40 In the preferred form of the invention I make the shelf of two plates of about equal width and arrange these plates to telescope together endwise, so as to lengthen or shorten the shelf.

In the accompanying drawings, Figure 1 is an end elevation illustrating a stenciling-machine with my improvements applied thereto, a sheet of paper being shown passing through the machine and about to drop upon the shelf 45 upon which other sheets have been piled. Fig. 2 is an end elevation of the shelf. Fig. 3

is a perspective view showing the shelf detached from the machine and partly extended.

The stencil-cylinder 1 is supported upon a framework 2. Against the under side of the 55 same bears a yielding pressure-roller 3, the latter carried upon arms 4, hinged upon a pair of bosses 5 at the opposite ends of the machine. A sheet of paper 6 is shown passing between the pressure-roller and the stencil-cylinder.

The improved delivery-shelf comprises a thin metal plate 7 of a width to extend substantially the usual length of the cylinder 1 and a similar plate 8, which has a telescopic 65 connection to the plate 7, so that the plates may be drawn out or pushed in to lengthen or shorten the shelf, considered as a whole. The side edges of the shelf 7 are folded underneath, as at 9, to form guides for the side 70 edges of the plate 8. The latter has at its free end a ledge 10, against which the leading edges of the sheets of paper 6^a rest, as at Fig. 1. At its upper end the plate 7 is provided with hooks 11, one at each side, to catch over 75 the bosses 5, whereby the shelf is detachably hinged upon the framework 2, between the ends thereof. The ledge 10 rests upon the table 12, and when the shelf is shortened or lengthened the shelf will turn upon the bosses 80 5 to permit the ledge end of the shelf to drop to the table.

Having thus described my invention, I claim—

1. A delivery-shelf for a stenciling-machine comprising a plate having a sheet-receiving ledge, and a second plate having its edges folded over to receive the first plate; means being provided for hanging the second plate loosely upon the stenciling-machine so that said ledge may rest upon the table.

2. A delivery-shelf for a stenciling-machine comprising a plate having a sheet-receiving ledge, and a second plate having its edges folded over to receive the first plate; and hooks provided upon the second plate for catching over bosses upon the stenciling-machine.

STEPHEN T. SMITH, JR.
